RETAINING STAND FOR SMALL CONTAINERS
OR SIMILAR ARTICLES

John M. Capozzi, 40 Orchard Ave., Rye, N.Y. 10580

Filed Aug. 12, 1968, Ser. No. 13,111

Term of patent 7 years

Int. Cl. D28—03

U.S. Cl. D86—10

Fig. 1

Fig. 2

Fig. 3

Fig. 4

Fig. 5

Fig. 6

I claim:

The ornamental design for a retaining stand for small containers or similar articles, substantially as shown.
